Primary Examiner — Marianne N Pandozzi*(74) Attorney, Agent, or Firm* — Medley, Behrens & Lewis, LLC; Lorri W. Cooper(57) **CLAIM**

The ornamental design for a beverage dispenser, as shown and described.

DESCRIPTION

FIG. 1 is a top perspective view of an example beverage dispenser;

FIG. 2 is a bottom perspective view of the beverage dispenser of FIG. 1;

FIG. 3 is a front plan view thereof;

FIG. 4 is a rear plan view thereof;

FIG. 5 is a right-side plan view thereof;

FIG. 6 is a left-side plan view thereof;

FIG. 7 is a top plan view thereof; and,

FIG. 8 is a bottom plan view thereof.

The broken line showings of FIGS. 1-8 are for illustrative purposes only and form no part of the claimed design.

1 Claim, 8 Drawing Sheets(56)
